UNITED STATES PATENT OFFICE.

LOUIS ROSENBAUM, OF NEW YORK, N. Y.

SAD-IRON.

1,073,171.

Specification of Letters Patent. Patented Sept. 16, 1913.

Application filed February 2, 1912. Serial No. 674,898.

To all whom it may concern:

Be it known that I, LOUIS ROSENBAUM, a citizen of the United States, residing in the city of New York, borough of Manhattan, 5 State of New York, have invented a certain new and useful Improvement in Sad-Irons, of which the following is a specification, reference being had to the accompanying drawings, forming a part hereof, in which—
10 Figure 1 is a rear elevational view of a sad-iron embodying my invention; Fig. 2 is a longitudinal sectional view on the line 2—2, Fig. 1; Fig. 3 is a detail sectional view on the line 3—3 Fig. 1; and Fig. 4 is a 15 perspective view of the rearward portion of said sad-iron and of the several parts of my new door and door-frame therefor disassembled.

This invention relates to a certain new 20 and useful improvement in sad-irons and more particularly to that class of sad-irons comprising a hollow base or body portion, usually a casting, open at its rear end and having a door for removably closing such 25 open end.

Heretofore, so far as I am aware, the open rear end of the base or body-portion of the class of sad-irons to which my invention particularly relates has generally 30 been removably closed by means of a door hingedly or pivotally mounted on a pin or pintle extending transversely through the walls of, and across, the base or body-portion of the sad-iron, such pin or pintle having 35 its ends upset and being thereby fixedly secured in operative position in such base or body portion. It has been the experience with such irons, however, that on either or both said pin or said door becoming broken 40 or damaged, and this has frequently occurred, the entire iron had to be discarded and replaced by a new one or the damaged iron repaired at comparatively great expense and difficulty.

45 The objects of my invention are, therefore, broadly to provide a sad-iron particularly of the kind stated with a removable door and door-frame, whereby, should either said door or said door-frame or 50 parts thereof become broken or damaged, the same may be easily replaced and the iron quickly repaired at slight expense; to provide a simple and efficient means for removably holding said door and door-frame 55 in operative position on such sad-irons;

and to improve generally upon irons of the class mentioned.

With these objects in view, my present invention resides broadly in the novel construction, arrangement, and combination of 60 the several parts of my new sad-iron door and door-frame and in the novel arrangement and combination of the same with a sad-iron, all as will hereinafter be described and afterward pointed out in the 65 claims.

In the drawings, wherein like reference characters refer to like parts throughout the several views, I have shown a particular style or kind of sad-irons, known in the 70 trade as a blower or compressed air and gas iron, adapted for use with, and with which I prefer to employ, my new door and door-frame, but it is to be understood that other styles or kinds of sad-irons 75 could readily be adapted for use with my new door and door-frame and that my new door and door-frame could equally well be employed with such other styles or kinds of sad-irons.

80

In said drawings, 1 indicates the base or body-portion of the sad-iron, said base or body-portion being usually and as shown a hollow metallic casting. At its forward end and in its top wall, said casting 1 is 85 provided with an opening through which a burner 2 is adapted to extend into the interior of said casting 1, as shown particularly in Fig. 2. This burner 2 comprises preferably a hollow cylindrical portion 3 90 having a rounded lower end, as at 4, adapted to seat in a correspondingly rounded recess in the bottom wall of the casting 1. A pipe or stem 5, adapted to be connected with any suitable source of gas and air 95 supply, is threaded into, or otherwise suitably secured to, the upper end of said hollow burner-portion 3, the said burner-portion 3 being provided, as is usual, with a suitable opening to permit the escape or 100 passage from said burner of mixed air and gas into the interior of casting 1. On the top wall of said casting 1 are provided a plurality of upstanding threaded lugs 6, upon which is adapted to rest and be secured, as by means of screws or the like 105 7, a suitable handle-plate 8 provided with a handle 9 preferably formed integrally therewith. The said burner 2 is also provided with a flange 10 having a tail-portion 110

10^a, said flange 10 and its tail-portion 10^a being preferably formed integrally with said hollow-portion 3 and being provided with an opening to receive, or permit the 5 passage therethrough of, said pipe or stem 5. This flange 10 and its said tail-portion 10^a have a thickness approximately equal to the distance between the lower surface of said handle-plate 8 and the upper surface of the 10 top wall of casting 1, said tail-portion 10^a being adapted, as shown, to fit between said handle-plate 8 and the top wall of casting 1 so as to hold said burner in operative position in said casting 1. Said body-portion 15 or casting 1 is also provided interiorly with what is known as a flame-spreader 11 removably held in proper position in casting 1 as by means of a screw or the like 12, as shown particularly in Fig. 2.

20 The vertical rear wall of casting 1 is provided with a preferably rectangular opening 13, the lower edge of which lies in a slightly lower horizontal plane than the top face or surface of the bottom wall of casting 1, as shown particularly in Figs. 2 and 4. A vertically-disposed rib 14 projects inwardly from each of the side walls of casting 1 on the interior thereof. These ribs 14 are arranged in casting 1 slightly forwardly from or in front of, and have their inner faces flush with, the vertical side edges of said rectangular opening 13, these ribs 14 with said side edges of said opening 13 forming or providing a slide or guide-way 25 15 for the door-frame 16, as shown clearly in Fig. 4. The top wall of casting 1 is cut-away, as at 17, see particularly Fig. 4, preferably flush with the outer faces of said ribs 14 to permit the easy insertion into, or 30 removal from, said guide-way 15 of said door-frame 16.

The door-frame 16 is preferably in the form of a rectangular casting of a size adapted to fit in said slide or guide-way 15 45 and comprising top and bottom cross members 18 and 19, respectively, and vertical side connecting members 20. Each of said side members 20 is provided with an outwardly-extending flange or guide-portion 50 21 adapted to slidably fit in said slide or guide-way 15, so as to maintain said door-frame 16 firmly and neatly in proper position in said opening 13. The rear faces of said side members 20 are also preferably 55 flush with the rear face of said top cross member 18, and said faces are also, when said frame 16 is in position on the casting 1, adapted to be or lie flush with the rear face of the rear wall of casting 1, as shown particularly in Figs. 1 and 2. It will also 60 be seen, as shown particularly in Fig. 1, that said top cross member 18 is preferably of such size or length as to extend neatly entirely across the top of casting 1 and 65 completely cover the cut-out portion 17 in

the top wall thereof. The lower cross member 19 of said frame 16 is preferably, as shown particularly in Fig. 4, in the shape of a rectangular bar extending between said side members 20 at the lower inner ends or 70 corners thereof.

22 indicates a door which is adapted to neatly fit in said frame 16, as shown particularly in Fig. 1, said door being hingedly or pivotally and removably supported in 75 operative position in said frame by means of a pivot-bolt or the like 23 adapted to loosely and removably fit in and extend through suitable openings 24 and 25 in said frame-side-members 20 and said door 22, 80 respectively, as shown particularly in Fig. 4. Each of said frame-side-members 20 is preferably recessed or cut-away on its inner side face, as shown, to provide a vertically-disposed ledge 26 against which said door 85 22 is adapted to rest or abut when in closed position in the frame 16 and a shouldered portion 27 adapted to fit in and coöperate with a correspondingly cut-away or recessed portion, as at 28, of said door 22. Extending laterally through said top cross member 18 is an opening 29 adapted to receive and hold a frame-securing screw 30, this screw 30 being adapted to be threaded through said opening and into a suitable 90 alining horizontally-disposed opening 31 in a lug or the like 32 on the top wall of casting 1 when it is desired to secure said frame 16 with its door 22 in proper operative position in casting 1, for it will be seen that, 100 when said screw 30 is in engagement with said lug 32, said frame 16 with its said door 22 will thereby be securely, but removably, held in proper operative position. I also 105 preferably swingably or pivotally arrange 105 on said screw 30 a suitable latch 33 adapted, as shown particularly in Fig. 1, to releasably hold said door 22 in closed position, said top member 18 of frame 16 being preferably provided, as shown, with a small 110 rearwardly-extending stud or pin 34 against which said latch 33 is adapted to rest when the same is swung or pivotally moved to permit said door to open. It will thus be 115 seen that said screw 30 not only serves to securely hold said frame 16 with its door 22 in proper position, but also serves as a pivot for said latch 33. On its outer surface, said door 22 is preferably provided with a suitable finger-piece, as at 35; and 120 by referring particularly to Fig. 2, it will be noted that the distribution of weight in door 22 is such that it always tends to fall rearwardly automatically upon latch 33 being released, contact with the lower edge of 125 said rectangular opening 13 retaining the said door when open in an approximately horizontally disposed position, so as not to interfere with the operation of the iron.

On assembling the several parts of my 130

iron, the door 22 is first placed in position in frame 16, when said bolt 23 is passed through said openings 24 and 25, after which said frame 16 is slidably fitted in 5 said slide or guide-way 15 and said screw 30 threaded into engagement with said casting-lug 32. Door 22 may now be freely swung on its pivot-bolt 23 longitudinally of body-portion 1 and opened or closed as 10 required, being held in closed position by means of latch 33, as described; and it will be observed that the side edges of said opening 13 in casting 1 prevent displacement or removal of said pivot-bolt 23 when 15 frame 16 is in operative position, whereby the use of securing-nuts or the like for such purpose is dispensed with.

From the foregoing, it will be seen that the several parts of my new door and door-frame may be easily constructed and readily assembled together and arranged and secured in operative position, and that, should any part thereof become broken or 20 in any way damaged, it is practically only necessary to remove screw 30 from engagement with said lug 32 to take out and replace the broken or damaged part.

I am aware that minor changes in the arrangement, construction, and combination 30 of the several parts of my new door and door-frame and in the arrangement and combination of the same with a sad-iron might be made and substituted for those herein shown and described without departing 35 from the nature and principle of my invention.

Having thus described my invention, what I claim and desire to secure by Letters Patent is:

40 1. A sad-iron comprising a hollow body-portion open at one end, a door-frame removably fitting in said body-portion at its open end, a door hingedly mounted in said frame adapted to close the open end of said body-portion, a screw adapted to engage with said frame and with said body-portion to removably secure said frame with its 45 said door in proper operative position in said body-portion, and a latch swingable on said screw adapted to releasably engage with said door to hold the same in closed position; substantially as described.

2. In a sad-iron, a hollow body-portion open at one end, an open substantially rectangular frame fitting in, and having its outer face substantially flush with the outer 55 end face, of said body-portion, a door fitting in said frame and adapted to close the open

end of said body-portion, the outer face of 60 said door being also, when said door is in closed position, substantially flush with the outer face of said frame and end face of said body-portion, and a pivot-bolt for hingedly supporting said door in said frame, said pivot-bolt extending longitudinally through 65 the body of said door and engaging the side members of said frame; substantially as described.

3. In a sad-iron, a hollow body-portion open at one end, a door-frame fitting in said 70 body-portion at its open end, a door removably fitting in said frame and adapted to close the open end of said body-portion, and a pivot-bolt for removably hingedly supporting said door in said frame, said pivot- 75 bolt extending longitudinally through said door and engaging the side members of said frame and being held in operative position by the side wall of said body-portion; sub- 80 substantially as described.

4. A door-frame and door for sad-irons comprising a rectangular open frame having top and bottom cross members and side-connecting members, a door fitting within the area of said frame, the outer face of said 85 door, when said door is in closed position, being substantially flush with the outer face of said frame, and a pivot-bolt extending through said door and into the side-members of said frame, said pivot-bolt being 90 adapted to hingedly support said door in said frame and said side-members being provided with inwardly-projecting shouldered portions against which said door is adapted to rest when in closed position; substantially 95 as described.

5. A sad-iron comprising a hollow body-portion provided with an opening at one end and a vertically-disposed slide-way in its interior in proximity to said opening, 100 the top wall of said body-portion being cut-away above said slide-way, a door-frame slidably fitting in said slide-way, a door fitting in said frame, and a pivot-bolt adapted to hingedly support said door in said frame, 105 said pivot-bolt removably engaging with said frame and said door and being held in position by the wall of said body-portion; substantially as described.

In testimony whereof, I have signed my 110 name to this specification, in the presence of two subscribing witnesses.

LOUIS ROSENBAUM.
